UNITED STATES PATENT OFFICE.

THEODORE A. HARTUNG, OF AUSTIN, TEXAS.

TATTING-SHUTTLE FILLER.

Application filed August 11, 1923. Serial No. 656,946.

To all whom it may concern:

Be it known that I, THEODORE A. HARTUNG, a citizen of the United States, residing at Austin, in the county of Travis and State of Texas, have invented a new and useful Tatting-Shuttle Filler, of which the following is a specification.

This invention relates to shuttle filling devices, and more particularly to a support for supporting the shuttle while the same is being filled.

Another object of the invention is to provide a support which may be readily and easily mounted on a sewing machine table, whereby the pulley forming a part of the support will engage the usual belt of a sewing machine to impart rotary movement to the shuttle for accomplishing the filling result.

A still further object of the invention is to provide means for securing the shuttle being filled, to the shaft of the support to insure against the shuttle becoming displaced or disconnected from its support, when the same is being rotated.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view disclosing the table and upper portion of the sewing machine supplied with a shuttle filling device constructed in accordance with the present device.

Figure 2 is a plan view of the support.

Figure 3 is a detail sectional view disclosing the means for securing the shuttle to its support.

Figure 4 is a sectional view on line 4—4 of Figure 2.

Figure 5 is a detail view showing the manner of securing the thread guiding arm.

Figure 6 is a back view of a modified form of shuttle holding means.

Figure 7 is a front elevation thereof.

Referring to the drawings in detail, the reference character 5 designates the base of the device which is formed with a cut

out portion disposed at one of the side edges thereof providing a clearance for the movable clamping member 6 which is formed with a hooked end 7 designed to grip one wall of the usual belt opening formed in the machine top. A coiled spring 8 has connection with the clamping member and has one end secured to the guide 9 which extends upwardly from the base and through which the clamping member moves.

Cooperating with the clamping member 6 is a downwardly extended hook member 10 which clamps the opposed wall of the opening 11 to secure the base 5 against movement. Bearing members 12 are formed on the base 5 and accommodate the rod 13 which is secured to the swinging frame 14, that is adapted to move to a position in proximity to the base 5 so that the device will consume comparatively little space in storing.

Forming a part of the frame 14 is a tubular member 15 in which is mounted the shaft 16 that carries a pulley 17 at one end thereof, a head 18 being formed on the opposite end of the shaft 15.

This head is formed with a curved shuttle engaging surface which is also provided with laterally extending pins 19 adapted to fit in suitable openings formed in one of the surfaces of the shuttle. Cooperating with the head 18 is a spring arm 20 that has a right angled extremity 21 contacting with the shuttle to force the same towards the head 18 to lock the head to the shuttle.

Pivoted supporting arms indicated at 22 are mounted on the base and have laterally extending fingers to be positioned in suitable openings formed in the arms 23 of the swinging frame 14, whereupon the swinging frame may be held in an upright position.

Secured to the base is a bracket member 24 designed to accommodate one end of the thread guiding arm 25 which has its opposite end formed into a relatively flat head 26 formed with an opening 27 to receive the thread being wound on the shuttle 28.

Thus it will be seen that upon positioning the body portion, the pulley 17 engages under the belt 29 forming a part of the usual sewing machine for transmitting motion to the shuttle supported by the shuttle supporting means. Due to the construction of the thread feeding arm, the thread feeding arm delivers the thread to a point with-

in the confines of the arms of the shuttle supported by the device, eliminating any possibility of the thread becoming tangled about the shuttle while being wound thereon.

In Figures 6 and 7 has been shown a modified form of shuttle holder comprising a dished plate 30 having spring fingers 31 provided with terminals 32 that lap on face 10 of the plate. The springs are soldered or otherwise fastened at intermediate points to the plate 30 as indicated at 33. This plate is designed to screw onto the shaft 16, there being a threaded recess 34 provided for this 15 purpose. A small stud 35 is provided on the concave face of the plate 30 for engagement with a correspondingly recessed portion on the shuttle.

Having thus described the invention, what 20 is claimed as new is:—

1. In a shuttle filling device, a body portion, a pivoted frame on the body portion and carrying a shaft at its upper end, means at one end of the shaft for securing a shuttle thereto, means for supporting the frame in an upright position, means for securing the device to the frame of a sewing machine to cause the shaft to be operated from the belt of the sewing machine, and a thread 25 guiding arm adapted to deliver thread directly to the shuttle, supported by the device.

2. In a shuttle filling device, a body portion, means on the body portion for clamping the same to a sewing machine table, a frame on the body portion, a shaft supported by the frame and carrying a pulley at one end thereof, said pulley adapted to 30 contact with the belt of the sewing machine to rotate the shaft, means at one end of the shaft for securing the shuttle thereto, and means for delivering thread to the shuttle.

3. In a shuttle filling device, a body por-

tion, a swinging frame on the body portion, a tubular member supported by the frame, a shaft supported within the tubular member, and carrying a pulley at one end thereof, said pulley adapted to underlie the sewing machine belt, to rotate the shaft, a shuttle securing means forming a part of the device, and a thread guiding arm removably secured to the body portion. 45

4. In a shuttle filling device, a body portion, a swinging frame mounted on the body portion, a shaft carried by the swinging frame, means for imparting rotary movement to the shaft, a shuttle supporting means at one end of the shaft, a guiding arm removably secured to the body portion, 50 said guiding arm having an inwardly extended end portion, a head formed at the end of the inwardly extended end portion and adapted to deliver thread within the confines of the shuttle, and means for securing the pivoted frame in an upright position. 55

5. In a shuttle filling device, a body portion, a swinging frame mounted on the body portion, clamping means for clamping the body portion to the table of a sewing machine, a shaft carried by the swinging frame and carrying a shuttle securing means at one end thereof, means for imparting rotary movement to the shaft, a removable 60 arm mounted on the body portion, and extending inwardly terminating at a point adjacent to the shuttle securing means to deliver thread thereto, and means for supporting the frame in an upright position. 65

In testimony that I claim the foregoing as my own, I have hereto affixed my signature in the presence of two witnesses.

THEODORE A. HARTUNG.
